UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 17,955, dated December 20, 1887.

Application filed November 10, 1887. Serial No. 254,873. Term of patent 3½ years.

To all whom it may concern:

Be it known that I, HENRIETTA F. DUKE, of the city, county, and State of New York, have invented and produced a new and original 5 Design for a Pattern of a Lady's Walking-Skirt; and I do hereby declare that the engraved prints accompanying this specification convey to any one accustomed to using paper patterns a clear understanding of how a garment made up by the pattern will appear.

The design shows a round walking-skirt that displays a pointed tablier falling low upon the skirt at the center, extending from the right-side back seam to the left-side front seam, and 15 exhibiting draping plaits at the belt and in the left-side edge some distance below the belt, and loopings that produce jabot and irregular

folds; a left back drapery that exhibits draping plaits at intervals down its front edge where it reaches nearly to the bottom of the skirt; 20 plaits at its back edge and loopings, and a right back drapery that displays draping plaits in its front and back edges, loopings, and falls in kilt-folds to the edge of the skirt below its loopings. 25

What I claim as my invention, and desire to secure by Letters Patent, is—

The design for a lady's walking-skirt, as shown in the engraved prints accompanying this specification.

HENRIETTA F. DUKE.
